UNITED STATES PATENT OFFICE.

ALEXANDER L. BOWER, OF PHILADELPHIA, PENNSYLVANIA, ASSIGNOR TO
THOMAS POTTER SONS & COMPANY, INCORPORATED, OF SAME PLACE.

DESIGN FOR FLOOR-CLOTH.

SPECIFICATION forming part of Design No. 34,424, dated April 23, 1901.

Application filed March 30, 1901. Serial No. 53,739. Term of patent 3½ years.

To all whom it may concern:

Be it known that I, ALEXANDER L. BOWER, a citizen of the United States, residing at Philadelphia, in the county of Philadelphia and State of Pennsylvania, have invented and produced a new and original Design for Floor-Cloth, of which the following is a specification, reference being had to the accompanying drawing, forming part thereof.

As shown in the drawing, the leading features of my design are comprised in the squares A, connected by the bars B, of irregular outline, which inclose the geometrical figure C.

Each of the squares A is outlined by a band a, within which is a dotted ground a', of color contrasting with that of the border, and within the ground a' are the figures a², a³, a⁴, a⁵, and a⁶ of contrasting colors.

Each of the bars B is outlined by a border formed by the irregular reversely-curved figures b, within which is a ground b', resem-

bling mosaic and of color contrasting with the border.

Each of the geometrical figures C is composed of the figures c, c', c², c³, c⁴, c⁵, and c⁶ of contrasting colors or differing outlines, the figure C being within a ground D, resembling mosaic and of color contrasting with its outer border.

Having described my invention, what I claim as new, and desire to secure by Letters Patent, is—

The design for a floor-cloth substantially as herein shown and described.

In testimony whereof I have signed my name to this specification, in the presence of the two subscribing witnesses, this 28th day of March, 1901.

ALEXANDER L. BOWER.

Witnesses:

THOMAS S. GATES,
PERCIVAL H. GRANGER.
